UNITED STATES PATENT OFFICE.

CARL O. WOLD, OF MINNEAPOLIS, MINNESOTA.

GRADING-MACHINE.

No. 918,633.

Specification of Letters Patent.

Patented April 20, 1909.

Application filed October 12, 1908. Serial No. 457,296.

To all whom it may concern:

Be it known that I, CARL O. WOLD, of Minneapolis, Hennepin county, Minnesota, have invented certain new and useful Improvements in Grading-Machines, of which the following is a specification.

My invention relates to road graders and the object of the invention is to provide a machine of simple durable construction, one which is capable of adjustment to suit the character of the soil in which the scraper blade is working and to permit tilting of the blade and adjusting at the desired angle with respect to the direction of movement of the machine.

Other objects of the invention will appear from the following detailed description.

The invention consists generally in various constructions and combinations all as hereinafter described, and particularly pointed out in the claims.

In the accompanying drawings forming part of this specification, Figure 1, is a plan view of a grading machine embodying my invention, illustrating the scraper blade adjusted at an angle to the direction of movement of the machine, Fig. 2, is a similar view illustrating the blade set at right angles to the direction of movement of the machine, Fig. 3, is a side elevation, Fig. 4, is a longitudinal vertical sectional view.

In the drawing, 2 represents a forward axle having a pole 3 and wheels 4 provided with flanges 5 which dig into the soil and hold the machine against skidding or lateral movement. A plate 6 is secured to the pole 3 and has an upwardly turned rear end 7 that fits within a socket in a draw bar 8 and is held therein by a cotter pin 9. The draw bar 8 is composed preferably of two channel bars secured together by bolts 10. A rectangular frame is provided, composed preferably of a forward channel bar 11 a rear channel bar 12 and end bars 13 connecting them. The rear bar 12 has a central pivotal connection with the draw bar 8 through a bolt 14. The forward channel bar has a series of holes 15 therein and a pin 16 is adapted to fit into one of said holes and into a slot 17 provided in the draw bar 8. A plate 17' is provided on the under side of the draw bar and has a series of holes to receive the lower end of the pin 16. Two bearing points are thus provided for this pin. This arrangement of the slot and pin, allows horizontal oscillation of the frame and its adjustment

with respect to the direction of travel of the machine. Angle bars 18 are secured to the end bars 13 and braces 19 extend from these angle bars to bolts 20 which pass through the webs of channel bars 21 and form the pivots therefor on the frame and particularly on the rear bar 12 thereof.

The scraper 22 is rigidly secured to the angle bars 18 and braces 23 extend from said scraper to the bar 12. Short independent crank axles 24 are journaled in the bars 21 and are provided with carrying wheels 25 similar to those on the front axle. Gear wheels 26 are mounted on the inner ends of the crank axles and are adapted to mesh with screws 27 provided on the lower ends of posts 28 which are supported in the flanges provided on the bars 21 and have operating wheels 29. By revolving these screws, the crank shafts 24 will be oscillated and the bars 21 raised or lowered to lift or depress the frame and tilt the scraper blade.

The bars 21 on opposite sides of the machine are held in parallel relation with one another by means of a link 28' that is pivoted at its ends to said bars 21. A turn buckle device 29' connects one of the bars 21 with the reach and enables the operator to set the rear wheels at a slight angle to the draw bar 85 and the direction of travel. This adjustment is of particular advantage where the ground is dry and hard and where increased resistance to the tendency to lateral movement on the part of the scraper blade is desirable. A seat 30 is provided on the rear end of the reach where the wheels 29 can be easily operated.

Each crank axle 24 being independent of the other crank axle, I am able to raise or lower one side of the machine without disturbing the adjustment of the other side, and with the bars 21 arranged parallel with the direction of movement or at an angle thereto.

I claim as my invention:—

1. In a grading machine, the combination with the draw bar, of a frame pivoted thereon and capable of horizontal oscillation means for locking said frame at an angle to the direction of movement of the machine and a scraper blade carried by said frame in front of the pivoted connection of said frame and draw bar, substantially as described.

2. In a grading machine, the combination with the draw bar, of a rectangular frame having channel bar sides and ends, the rear side bar having a pivotal connection on said

- draw bar and the forward rail of said frame having an adjustable connection with said draw bar and a scraper blade carried by said frame the pivot of said frame and said bar being in the rear of said scraper.
3. In a grading machine, the combination with the draw bar of a frame pivoted thereon and provided with a series of perforations, a pin adapted to fit into said perforations and into a longitudinal slot provided in said draw bar and a scraper blade carried by said frame in front of the pivotal connection of said bar and said frame.
4. In a grading machine, the combination with the draw bar of a frame mounted thereon, a scraper blade carried by said frame, bars pivoted on said frame and extending rearwardly therefrom crank axles having carrying wheels journaled in said bars and means for oscillating said crank axles to raise and lower said bars and frame.
5. In a grading machine, the combination with the draw bar, of a frame pivoted thereon, a scraper blade carried by said frame, bars pivoted at their forward ends, crank axles journaled in said bars and having carrying wheels; means for oscillating said crank axles, means connecting said bars with one another to hold them in parallel relation.
6. In a grading machine, the combination with the draw bar, of a frame pivoted thereon, a scraper blade carried by said frame, pivoted bars projecting rearwardly from said frame, crank axles journaled in said bars and having carrying wheels, means for raising and lowering said axles, means connecting said bars with one another, said bars being normally in line with the direction of travel of the machine, and means for adjusting said bars at an angle to the direction of movement of the machine.
7. In a grading machine, the combination with a scraper frame and a blade carried thereby, of bars projecting rearwardly from said frame, crank axles journaled in said bars and having carrying wheels and posts geared to said crank axles and having an operating means, substantially as described.
8. In a grading machine, the combination with a frame, and a scraper blade carried thereby, of bars pivotally connected with said frame and extending rearwardly therefrom, crank axles journaled in said bars and having carrying wheels and means for oscillating said crank axles independently of one another, substantially as described.
9. In a grading machine, a frame and a scraper blade carried thereby in combination with pivoted bars and crank axles journaled therein, carrying wheels for said crank axles, means connecting said bars with one another to insure their simultaneous lateral oscillation and means for oscillating said crank axles.
10. In a grading machine, a frame, a scraper blade carried thereby, pivoted bars, crank axles journaled in said bars and having carrying wheels, means for oscillating said crank axles and a link connecting said bars with one another and holding them in parallel relation.
11. In a grading machine, the combination with forward and rear axles and carrying wheels therefor, of a draw bar, a frame arranged to oscillate horizontally on said draw bar and a scraper blade carried by said frame and arranged to oscillate therewith the pivot of said frame and draw bar being in the rear of said scraper.
12. In a grading machine, the combination, with a draw bar, of a frame pivoted thereon and capable of horizontal oscillation, a scraper blade carried by said frame, said frame having a pivotal connection with said bar in the rear of said blade, and a sliding connection therewith in advance of said blade.
13. In a grading machine, the combination, with a draw bar, of a frame pivoted thereon and capable of horizontal oscillation, a scraper blade carried by said frame, said frame having a pivotal connection with said bar in the rear of said scraper blade, and a sliding adjustable connection with said bar in front of said blade.

In witness whereof, I have hereunto set my hand this 5th day of October 1908.

CARL O. WOLD.
